UNITED STATES PATENT OFFICE.

JOHN D. BOWMAN, OF ALTOONA, PENNSYLVANIA.

VALVE.

SPECIFICATION forming part of Letters Patent No. 429,881, dated June 10, 1890.

Application filed January 23, 1889. Serial No. 297,286. (No model.)

To all whom it may concern:

Be it known that I, JOHN D. BOWMAN, of Altoona, county of Blair, State of Pennsylvania, have invented a new and useful Improvement in Valves, of which the following is a true and exact description, reference being had to the accompanying drawings, which form a part of this specification.

My invention relates to the construction of valves, and is especially intended for use with the needle-valves employed to control the flow of carbureted air or gas in those systems of railway-car lighting in which gas is employed. Obviously, however, my device is capable of use in many other connections.

The object of my invention is to avoid the use of stuffing-box glands or similar devices, and to so arrange the actuating-rod of the valve as to prevent leakage around it.

The leading features of my device consist of a valve-casing, a valve having a short stem entirely inclosed in the casing, and having only longitudinal motion therein, a valve-actuating rod so connected with the valve-stem as to give it longitudinal motion, and having a projection upon its stem formed to fit tightly with a seat on the inside of the cap of the casing, and a spring inclosed in the casing, so as to act to press the actuating-rod outward.

An important additional feature which I prefer to employ consists in inserting the spring between the valve-stem and the actuating-rod, so that as the valve opens it will press with increased force against said rod.

The novel features of my invention are hereinafter clearly pointed out in the claim, and will be best understood after a description of the device as it is shown in the drawings, which represent my invention embodied in what I believe to be its best form, and in which—

Figure 1 is a central sectional elevation showing my improvement in its said preferred form, and Fig. 2 a cross-section on the line $x-x$ of Fig. 1.

A is the valve-casing, to which the conduit-pipes are attached in the usual way at A' and A², the gas passing from A' through a, thence to a', and thence through A². The portion of the valve-casing lying below the passage a, through which the gas passes to the interior of the

chamber, is threaded, as is shown at A⁴. Below this threaded portion the chamber of the casing is enlarged, as is shown at A⁵, the lower end of this enlarged opening being threaded, 55 as is shown at A³, to receive the threaded end C' of the cap C, which said cap is centrally perforated, as is shown at C³, to permit the valve-key to pass through it, the upper portion of said perforation being formed into a 60 seat C².

B is the valve, the stem of which is threaded, as is shown at B', and screwed into the thread A⁴ of the casing. Below the threaded portion of the valve-stem it terminates in a 65 shank B², which may be of any convenient shape in cross-section, except round. Preferably I form a flange B³ on the valve-stem above the shank B².

D is the valve-key, the upper end of which 70 must be formed so as to engage the shank of the valve-stem and turn with it without interfering with its longitudinal motion. On this key is a flange D², and below the flange a face D' is formed on the key, which fits and forms a 75 tight joint with the seat C² of cap C. Below the face D' extends the shank D³ of the key, the end of which is squared off at D⁴ and terminates in a screw D⁵.

E is the handle by which the valve-key is 80 turned. It has a square perforation E', which fits on the square perforation D⁴ of the key, and is held in place by a nut F screwing on the end D⁵ of the key. To prevent chattering I use a washer G, of leather or other soft 85 material, which is placed between the handle E and the end of the cap C, as shown.

H is a spring, which is placed inside of the valve-casing, resting at one end on the flange D² of the valve-key, and preferably resting at 90 its other end against the flange B³ of the valve-stem. If this flange B³ be omitted, the upper end of the spring can rest against the shoulder A⁵ of the valve-casing, although, for reasons which I will hereinafter give, it is 95 very much better to secure the spring between the two flanges B³ and D², as shown in the drawings.

The operation of my device is as follows: The parts being put together, as shown in the 100 drawings, it is evident that by turning the key D the valve-stem will be compelled to turn with

it, and in turning will, by reason of its screw-connection with the valve-casing, advance or recede from its seat in the passage *a*. The key D will have no longitudinal motion, and its face 5 D' will be constantly held on the seat C² by the pressure of the spring H. Where, as in the modified form suggested by me, the spring H extends to the shoulder A⁵ its pressure is constant; but when the spring is clamped between the shoulders B³ and D², as shown in the drawings, it is compressed whenever the valve is opened, and the more gas that is allowed to pass through the chamber the tighter 10 the face D' of the valve-key is pressed against the seat C² in the cap, and the less danger there is of the escape of the gas around the key.

The function of the washer G is to prevent chattering and noise, which it does by keeping 15 all of the parts pressed together with sufficient force to prevent their rattling on each other without offering any material frictional resistance to the turning of the handle.

Having now described my invention, what I claim as new, and desire to secure by Letters Patent, is—

In combination with a chambered valve-casing, a valve having a stem with an angular shank B², and a flange B³, fitting the interior of the chamber, a chambered cap for the casing, a valve-actuating key extending through the cap and having a cylindrical head recessed to fit the valve-stem shank and having a flange D² fitting the interior of the chamber, a seat in the end of the chamber, and a 30 projection on the key beyond the flange conforming to said seat, a spring seated in the annular space between the head and the walls of the chamber and reacting between the flanges B³ and D², a handle on the key-actuating rod, and a washer interposed between the handle and the end of the cap.

JOHN D. BOWMAN.
